UNITED STATES PATENT OFFICE.

JOHN McGEORGE, OF LAKEWOOD, OHIO, ASSIGNOR TO THE OHIO BODY & BLOWER COMPANY, OF CLEVELAND, OHIO, A CORPORATION OF OHIO.

VENTILATOR.

1,378,476.

Specification of Letters Patent. Patented May 17, 1921.

Application filed March 4, 1918. Serial No. 220,170.

To all whom it may concern:

Be it known that I, JOHN McGEORGE, a citizen of the United States, residing at Lakewood, in the county of Cuyahoga and State of Ohio, have invented a certain new and useful Improvement in Ventilators, of which the following is a full, clear, and exact description, reference being had to the accompanying drawings.

10 This invention relates to ventilators, and has for its general object to produce a ventilator cowl which can not only be manufactured in a particularly simple and inexpensive manner but which will combine such 15 economy of production with a maximum efficiency of operation.

The cowl illustrated and described herein is one which is designed more particularly for use with vessels, in connection with the 20 production of a forced draft, but it will be understood that it is adapted for use as the cowl of an exhaust ventilator and for uses other than marine installations.

Cowls of the general type illustrated 25 herein have usually been constructed from a plurality of metal sheets extending transversely of the length of the cowl, and with no special relation between the cross sections of the enlarged or flaring portions of the 30 cowl and the cross section of the lower or air-shaft end thereof. The cowl forming the subject matter hereof employs in its construction longitudinally and transversely curved metal sheets extending longitudinally of the cowl and the cowl is so shaped 35 that the cross section of its enlarged end preferably bears a definite relation to the cross section of the lower or air-shaft end thereof. Furthermore the cowl is so shaped 40 and certain of the metal sheets thereof (the central longitudinal front sheet and the central longitudinal rear sheet) are so arranged and shaped as to enable them to be produced by a rolling operation, whereby the cost of 45 production of these sheets and of the cowl is materially decreased as compared with the construction of any other cowl or cowls that have heretofore been constructed.

In the drawings forming part hereof, 50 Figure 1 represents a side elevation of a cowl embodying the invention; Fig. 2 a rear elevation of such cowl; and Figs. 3, 4, and 5 are cross sectional views corresponding respectively to the lines 3—3, 4—4 and 5—5 of 55 Fig. 1.

Describing the various parts illustrated herein by reference characters, 1 denotes the lower or air-shaft end of the cowl, said lower end being circular in cross section and, in the embodiment shown herein, merging 60 with the flaring upper end of the cowl. As illustrated herein, the mouth of the cowl is elliptical, the longer axis of the ellipse being vertical.

The cowl is shown as formed from longitudinally extending metal plates, the front plate 3 and the rear plate 4 being curved longitudinally in accordance with the particular longitudinal curvature to be given to the cowl and being transversely curved on 70 an arc of a circle the radius whereof is the radius of the lower end or air-shaft portion 1 of said cowl, as indicated by the circles on Fig. 2. The front plate 3 and the rear plate 4 are preferably of uniform width 75 throughout their longitudinal extent and the space between said plates is closed by means of side plates 5 which are longitudinally and transversely curved so as to form with said front and back plates a chamber varying 80 in cross-section from a circle at the lower end of the cowl to approximately an ellipse at the upper and front end thereof.

It has been found to be of material advantage in constructing the cowl to make the 85 mouth approximately in the shape of an ellipse, the major axis whereof is preferably twice the diameter of the lower circular portion of the cowl, the minor axis being about one and one half times the diameter 90 of such lower portion, as indicated on Fig. 2. This shape not only facilitates the shaping of the plates but secures a maximum efficiency in the movement of the air with a minimum expenditure of metal.

By giving to the front and back plates the peculiar form shown and described, these plates may be rolled to shape, which enables the cowl to be produced at a material saving of labor and expense over any other 100 cowls of like dimensions with which I am familiar; this peculiar form also enables these plates to be formed by dies which can be easily designed, cheaply constructed and which will form the plate by substantially a 105 mere stretching operation. Furthermore, by the shape of the cowl as a whole (the major axis of the elliptical mouth being one and one third times the minor axis) a maximum efficiency is secured in the movement 110

of the air through the cowl with a minimum expenditure of metal.

At the mouth of the cowl, the plates 3, 4, and 5 are inserted into a split pipe, forming 5 a bead 6, as indicated in dotted lines in Fig. 2, and the longitudinal edges of said plates are united in any convenient manner, as by rivets, indicated at 7.

In the description and claims, as a matter 10 of convenience of terminology, it has been assumed that the cowl will be used in connection with the production of a forced draft, and the terms "front" and "rear" or "back" have been employed to designate their relation to a cowl thus employed. However, 15 it is not intended thereby to preclude the use of the cowl in connection with an exhaust ventilator, wherein the arrangement of the parts will be reversed.

20 Having thus described my invention, what I claim is:—

1. A ventilator cowl comprising a lower portion substantially circular in cross-section and an enlarged longitudinally curved 25 upper portion extending therefrom, said cowl having a front plate of constant width extending longitudinally thereof and transversely curved throughout its entire length on a radius substantially equal to the radius 30 of the lower portion of said cowl.

2. A ventilator cowl comprising a lower portion substantially circular in cross-section and an enlarged longitudinally curved upper portion extending therefrom, said 35 cowl having a back plate of constant width extending longitudinally thereof and transversely curved throughout its entire length on a radius substantially equal to the radius of the lower portion of said cowl.

40 3. A ventilator cowl comprising a lower portion substantially circular in cross-section and an upper enlarged portion extending therefrom and having an elliptical mouth, said cowl comprising a front plate 45 and a back plate both of which are of constant width and longitudinally curved and each of which is transversely curved throughout its entire length on a radius substantially equal to the radius of the lower portion 50 of said cowl.

4. A ventilator cowl comprising a lower portion substantially circular in cross-section and an upper enlarged longitudinally curved portion extending therefrom, said 55 cowl having longitudinally curved front and back plates of constant width, each of said plates being also transversely curved throughout its entire length on a radius sub-

stantially equal to the radius of the lower portion of said cowl, said cowl having an 60 elliptical mouth the major axis whereof is substantially twice the radius of the lower portion of said cowl.

5. A ventilator cowl comprising a lower portion substantially circular in cross-section and an upper enlarged longitudinally curved portion extending therefrom, said cowl having longitudinally curved front and back plates, each of said plates being of constant width and also transversely 70 curved throughout its entire length on a radius substantially equal to the radius of the lower portion of said cowl, said cowl having an elliptical mouth the major axis whereof is substantially twice the radius of 75 the lower portion of said cowl and the minor axis thereof is substantially one and one-half times said radius.

6. A ventilator cowl comprising a lower portion substantially circular in cross-section and a longitudinally curved and flared upper portion extending therefrom, said cowl having front and back plates each of which is of constant width and longitudinally curved and each of which is transversely curved on a radius substantially equal to the radius of the lower portion of 80 said cowl, and intermediate longitudinally and transversely curved plates connecting the front and back plates, the said plates 85 providing at their upper ends an elliptical mouth the major axis whereof is substantially twice the diameter of the lower portion of the cowl and the minor axis whereof is substantially one and one-half times such 90 diameter.

7. A ventilator cowl comprising a lower portion substantially circular in cross-section and a longitudinally curved and flared upper portion extending therefrom, said 100 cowl having a front and a back plate each of which is of constant width and longitudinally curved and each of which is transversely curved on a radius substantially equal to the radius of the lower portion of said cowl, and intermediate longitudinally and transversely curved plates connecting the front and back plates, the said plates 105 providing at their upper ends an elliptical mouth the major axis whereof is substantially twice the diameter of the lower portion of the cowl.

In testimony whereof, I hereunto affix my signature.

JOHN McGEORGE.
